TYPE BINDER

John J. Riehl, Cleveland, Ohio

Application October 11, 1939, Serial No. 299,031

5 Claims. (Cl. 101—404)

This invention relates to printing and particularly to devices used to hold together loose type, type slugs, electrotype and similar printing members, while being transferred in a set or composed form from a galley to a chase.

As conducive to a clearer understanding of this invention it may be well to point out, that in most printing plants the type composed for individual pages or columns is assembled in metal trays known as galleys. The assembled type, other printing members and spacers of each page are generally tied together with ordinary string or ribbon so as to preserve their formation until ready to be put on the press.

In many plants the type is held in place with clamps, generally known as galley locks, until ready for imposition. The galley locks, however, do not circumscribe the type members but merely hold the members in a fixed position in the galley. Galley locks of this type are shown and described in my United States Letters Patent No. 2,173,728, granted September 19, 1939.

When composed type is ready for the press, it must be removed without becoming pied along with the other page forms, from the galley and then firmly locked in the heavy metal frame known as the chase. The instant invention relates to the mechanism or device which holds the separable type members together during the interval after the galley locks are removed and before the form is bound by the chase.

The primary object of the invention is to provide a permanent device which will eliminate the necessity of tying composed type together with string, tape or similar material.

Another object of the invention is to construct a device of the character mentioned which is simple and inexpensive to manufacture and use and which may be applied or used by those familiar with the printing trade without special skill or training.

These and other objects as well as a fuller understanding of the invention may be had by referring to the following description and claims together with the accompanying drawing in which like parts are designated by like reference characters, and in which:

Figure 1 is an orthographic projection of the type binder constituting this invention as it engages or holds together some composed type and type slugs;

Figure 2 is a similar view of the binder alone;

Figure 3 is a sectional view of the binder showing the first step in the assembly of the corner members and side sections;

Figure 4 is a sectional view of a member and section taken along the lines 4—4 of the Figure 2;

Figure 5 is a similar view taken along the lines 5—5 of the Figure 2; and

Figure 6 is a cross-sectional view taken along the lines 6—6 of the Figure 5.

This device consists primarily of two different kinds of elements of which there are four of each. There are first the four corner members, sometimes referred to herein as confining members or holder members; and the side sections, sometimes referred to herein as resisting members, straight members, friction grip members, second holder members, cushion members or channel members.

A corner member consists of a flat strip of hard stiff metal 10 about five-eighths of an inch wide, or slightly narrower than the height of a type-body, and anywhere from four to twenty inches long. This corner member 10 is bent intermediate its ends 11 so as to form right angularly abutting walls 12 and 12a. One end of the bent strip 10, namely, the wall 12, has a small hole 13 therethrough about one-eighth of an inch in diameter, and the opposite end or wall 12a is provided with a small protuberance or nodule 14 which engages a hole of an adjacent corner member. The nodule 14 is formed with a more inclined side facing the end 11a and a more vertical side facing its inner angle or bent portion. This construction permits the adjacent walls 12 and 12a, which are side by side, to slide inwardly on each other more easily than in an outward direction. The more vertical side of the nodule 14, after it engages the hole 13, acts as a snag or impediment to further outward movement or separation of the two adjacent walls 12 and 12a. However, the engagement is such that the walls 12 and 12a may be separated as shown in the Figure 3 when extraordinary expansion is required. On such occasions, simply bending the walls so as to move the wall 12a away from the end 11, will disengage the nodule 14 from the hole 13.

To facilitate assembly of the parts and to make their operation easier and smoother, the ends 11 and 11a are tapered and have their corners rounded. The tapered walls prevent jamming and the rounded corners eliminate the possibility of sharp corners damaging the rubber tube member herein-after described.

A side section 20 consists of two flat stiff pieces of metal 21 and 21a, each of the same length and slightly wider than the corner member strip 10. The extreme ends 22 of the metal pieces 21 and 21a are flared or bent outward so as not to restrict

50

55

the movement of the walls 12 and 12a. Encasing the two metal pieces 21 and 21a, there is a flattened rubber tube 23, the normal diameter of which is somewhat less than the width of the metal strips 21 and 21a. This rubber tube 23 is just long enough to fit neatly between the flared ends 22 and is resilient enough to hold the confining members 21 and 21a together rather tightly. The rubber tube 23, in addition to being the means for holding the confining members together under tension, also serves as a buffer or bumper on the binder, which prevents accidental damage to the type or printing members 17.

In assembly, one of the walls 12 is inserted into the constricted channel formed by the confining members 21 and 21a and the rubber tube 23. Next, one of the walls 12a on another corner member, is inserted therein until the nodule 14 engages the hole 13. This operation is repeated until all four corner members and all four side sections form an adjustable or variable sized rectangular enclosure.

In actual use, all that the compositor need do is to select a binder nearest to the sized page or column he is working on; expand the corner members and side sections slightly so as to easily enclose the composed type, and then when placed around the type, compress the members snugly around it. It has been found in practice that when this device is made of suitable materials and proper dimensions, an ordinary page of Monotype can be held together and conveniently and rapidly handled while being transferred from the galley to a chase. It might also be mentioned that frequently printers have a need for cleaning such composed type with gasoline, and as ordinary natural rubber deteriorates quickly when moistened with gasoline, it is advisable to use artificial rubber known commercially as Neoprene for the side tubes 23.

It will now be clear that there is provided by this invention a type binder which accomplishes the objects of the invention. While the invention has been described in a specific form and while certain general terms and special language have been used, it is to be understood that the embodiment of the invention as described is suggestive

only and is not to be considered in a limiting sense. It is to be further understood that, as there are other forms or adaptations of the invention which will suggest themselves to persons making, using or selling similar devices, those modifications as well as the modifications of the illustrated form are also considered to be within the broad scope of the invention as no limitations upon it are intended other than those imposed thereon by the scope of the appended claims.

10

I claim:

1. A type binder, comprising in combination, a plurality of first holder members having right angularly abutting corner walls, a plurality of second holder members forming side walls, a plurality of channel members engaging the first and second holder members in adjustable rectangular formation, and a plurality of resilient cushion members mounted on the said assembled confining and resisting members.

15

2. A type binder, comprising in combination, a plurality of side members each consisting of parallel engaging plates mounted within a resilient channel section, and a plurality of corner members each having ends tractably engaged by the said plates and forming a rectangular assembly.

20

3. In a type binder of the character shown and described, a side member, comprising, in combination, a plurality of longitudinal plate sections, and a length of resilient tubular material engaging the said plate sections under tension and forming a longitudinal channel therewith.

25

4. A type binder, comprising in combination, a plurality of corner members having tapered ends thereon, and slidably resilient means for retaining the tapered ends of adjacent corner members in an assembled relation.

30

5. A type binder, comprising in combination, four right-angled corner members having ends thereon, one of the ends of each of the corner members having a hole therein and the other of the ends of each of the corner members having a nodule thereon engageable with the said hole in the end of the next adjacent corner member; and means for retaining the said ends in an assembled relation.
